UNITED STATES PATENT OFFICE.

MARTIN LEE, OF ALMA CITY, MINNESOTA.

HAND-CAR AND TRACK-RAISER.

SPECIFICATION forming part of Letters Patent No. 393,015, dated November 20, 1888.

Application filed June 29, 1888. Serial No. 278,550. (No model.)

To all whom it may concern:

Be it known that I, MARTIN LEE, a citizen of the United States, residing at Alma City, in the county of Waseca and State of Minnesota, 5 have invented new and useful Improvements in a Hand-Car and Track-Raiser, of which the following is a specification.

My invention relates to a combined hand-car and track-raiser, having for its object to provide suitable simple and portable raising devices attached to a hand-car, whereby the track may be raised at any point to repair or insert sleepers.

The invention consists in a certain novel construction and arrangement of devices, fully set forth hereinafter in connection with the accompanying drawings, wherein—

Figure 1 is a perspective view of a hand-car provided with the track-raiser embodying my 20 improvements. Fig. 2 is a bottom plan view of the same. Fig. 3 is a transverse sectional view on the line $x-x$ of Fig. 2, showing the clutches engaged with the track and the device in position to raise the same. Fig. 4 is a 25 longitudinal central sectional view with the clutches raised out of engagement with the tracks. Fig. 5 is a detail view of one of the raising-levers. Fig. 6 is a detail view showing the spring-dog which locks the vertical shaft 30 in place.

Referring to the drawings, A designates a hand-car of the ordinary and well-known construction provided with the wheels $a-a$, which are mounted on rigid axles $a'-a'$. On a transverse shaft, a^2 , which is mounted on the under side of the car parallel with and adjacent to one of the axles, is arranged the gear-wheel a^3 , which meshes with a pinion, a^4 , on the said axle, and B designates the operating-lever, which is 35 mounted on suitable standards, $b-b$, on the upper side of the car, and is provided with the arm b' , connected at its free end to a suitable crank, a^5 , in the shaft a^2 by means of the rod or link b^2 , which passes through an opening, 40 a^6 , in the platform of the car.

A transverse opening, C, is formed in the platform of the car, and near the ends of the same, adjacent to the sides of the car, are the vertical movable standards D, which are 45 mounted in openings e in the plates E, which are affixed to the platform of the car and ex-

tend over the opening therein. These standards are preferably squared, and fit in the squared openings e, to prevent them from turning, and they are provided at their lower ends 55 with the pivoted or swiveled feet or bases d d, adapted to bear on the ground between the tracks, and at their upper ends with the adjacent parallel racks d' d', which are formed by bending a flat extension of the standard on itself and providing the edges with ratchet-teeth. Spring-actuated dogs F are mounted on the plates E, and are adapted to engage sockets d² in the standards when the latter are raised, as shown in Fig. 4 of the drawings, and the said 60 dogs are provided at their free ends with the vertical studs or handles f, whereby they may be disengaged from the said sockets by the foot of the operator. (The dogs are adapted to engage the sockets d² automatically when the 65 standards are raised.)

In bearings g in the transverse plates G, which are affixed to the platform of the car over the opening C therein, are mounted the vertical raising-bars H H, which are provided 75 at their upper ends with the heads or nuts h h and at their lower ends with the hooks or cams h' h', the said bars being so arranged that when they are extended downward they will pass at their lower ends on the inner sides of the 80 rails, whereby when they are turned the hooks or cams engage under the treads of the adjacent ribs. The raising-bars are further provided, just above the said hooks or cams, with the shoulders h², and also with the collars h³, 85 adjacent to the shoulders, the portions of the bars between the shoulders and the collars forming spindles, which are mounted in bearings j j near the ends of the clutch-bar J. The bar J is provided at its ends with the depending arms or studs j², which are adapted to pass 90 down on the outer sides of the rails.

It will be observed that when the raising-bars are turned to engage the hooks or cams on their lower ends with the treads of the rails 95 the latter are firmly clamped between the hooks or cams and the depending arms or studs j², the said parts thus forming clutches.

K represents a vertical shaft, which is mounted in a bearing, l, in the plate L, (which 100 is arranged across the center of the opening C,) and it is provided at its lower end with a

finger, k , which is adapted to be engaged under the center of the clutch-bar J , whereby the latter (and consequently the raising-bars which are attached thereto) may be raised out of contact with the rails when the hand-car is in motion. This shaft is provided at its upper end with a hand-wheel, k' , to enable it to be rotated and raised, and on the plate above mentioned is arranged a spring-actuated dog, M , engaging sockets $k'' k''$ in the shaft K in either its raised or lowered position, the said dog being adapted to prevent both vertical and rotary movement of the shaft.

The shaft K is provided below the platform of the car with the lateral arms $N N$, which are connected, respectively, to similar arms, $O O$, on the raising-bars by means of connecting-links $P P$, whereby when the said shaft is turned the raising-bars are similarly operated to enable the hooks or cams on their lower ends to be engaged with the rails or disengaged therefrom. When the hooks or cams are engaged with the rails, the vertical shaft is locked against movement by the dog above mentioned, which automatically engages one of the sockets k'' .

From the above description it will be understood that by proper manipulation of the shaft K the clutches may be lowered and engaged firmly with both rails simultaneously and locked in the said engaged position, and also that the clutches may be disengaged and raised simultaneously and locked in the latter position.

I will now proceed to describe the mechanism for raising the rail after the raising-bars are engaged therewith and the standards are bearing at their lower ends on the ground.

$R R$ represent vertical links, which are provided at their lower ends with sockets $r r$, swiveled on the raising-bars below the heads or nuts thereon, and to the upper ends of the links are pivoted the raising-levers $S S$. The head of the raising-lever consists of a flat plate, s , provided at its upper edge with the inturned hooks $s' s'$, adapted to engage the ratchet-teeth on the upper end of the standard and the intermediate guiding-tongue, s^2 , between the hooks, and adapted to operate between the racks $d' d'$, and thereby guide the vertical movement of the lever.

It will be observed that the links R are swiveled loosely on the raising-bars, whereby the hooks $s' s'$ on the levers may be engaged, respectively, with the racks on the standards. The center of the heads or plates s are pivoted on the upper ends of the links, so that the said hooks are on opposite sides of the pivot, and therefore to raise the track operate the levers to alternately engage their hooks with corresponding teeth in the racks—namely, engage the inner hooks, s' , with the corresponding rack, then engage the outer hook with the next higher tooth of the corresponding rack, then engage the inner hook with the next higher tooth of the first-mentioned rack, and so on

until the rail is raised sufficiently, (it being understood that both levers may be operated at the same time, so that both rails are raised equally, or either lever may be operated to raise one track.)

In the improved track-raiser the strain is entirely sustained by the parts of the raising mechanism, for the reason that the raising-bars are connected at their lower ends to the rails by means of the clutches, the standards bear directly on the ground, and the raising-levers which operate on the standards are connected directly to the raising-bars, thus preventing strain from falling on the hand-car. The rails are held in their raised position by the levers, both hooks of which are allowed to engage approximately opposite teeth of the adjacent racks.

Having thus described the invention, I claim—

1. In a track-raiser, the combination of the standard provided with parallel vertical racks, the raising-bars provided at their lower ends with clutches to engage the track-rail, and the levers connected to the raising-bars and provided with hooks $s' s'$, adapted to alternately engage the racks on the standards, substantially as specified.

2. In a track-raiser adapted to be mounted on a hand-car, the standards provided with parallel racks $d' d'$, in combination with the raising-bars provided at their lower ends with clutches engaging the rails, and the raising-levers connected to the upper ends of the raising-bars and provided with hooks $s' s'$, adapted to engage the racks on the standards alternately, substantially as and for the purpose specified.

3. In a track-raiser, the standards provided with the parallel racks $d' d'$, in combination with the raising-bars provided at their lower ends with clutches engaging the rails, the levers connected to the raising-bars and provided with the hooks $s' s'$, adapted to alternately engage the said racks, and the intermediate tongue fitting between the said racks, substantially as and for the purpose specified.

4. In a track-raiser, the standards provided with parallel racks in combination with the raising-bars provided at their lower ends with clutches engaging the rails, the links R , swiveled on the upper ends of the said bars, and the levers $S S$, pivoted on the upper ends of the links and provided on opposite sides of the said pivot with the hooks $s' s'$, adapted to alternately engage the said parallel racks, substantially as specified.

5. In a track-raiser, the vertical standards mounted on a hand-car and provided with suitable racks, in combination with the clutch-bar J , provided with depending arms or studs at its ends extending down on the outer sides of the rails, the raising-bars swiveled at their lower ends in bearings in the clutch-bar and provided with hooks or cams to engage under the treads of the rails, and the levers connected

to the raising-bars and adapted to engage the racks on the standards, substantially as and for the purpose specified.

6. In a track-raiser, the vertical standards 5 mounted on a hand-car and provided with suitable racks, the clutch-bar J, provided with the depending arms or studs j^2 , the lifting-bars swiveled in the clutch-bar and provided with hooks or cams in their lower ends, 10 and the levers connected to the upper ends of the raising-bars, in combination with the vertical shaft mounted on the hand-car at its center and provided with a finger to engage the center of the clutch-bar J, and the locking 15 means to hold the said shaft in the raised position, substantially as and for the purpose specified.

7. In a track-raiser, the vertically-movable standards mounted on a hand-car and provided with racks on their upper ends and swiveled feet or bases on their lower ends, the spring-actuated dogs engaging sockets in the standards to hold them in their raised positions, the clutch-bar J, provided with the depending 25 arms or studs j^2 , the raising-bars swiveled in the clutch-bar and provided with hooks or cams on their lower ends, the levers connected to the upper ends of the raising-bars and adapted to engage the racks on the standards 30 to raise the said raising-bars, the vertically-

movable shaft mounted at the center of the hand-car and provided with a finger on its lower end adapted to engage the clutch-bar, whereby the latter may be raised when not in use, and the spring-dog adapted to engage 35 sockets in the said shaft to lock it in the desired position, substantially as specified.

8. In a track-raiser, the vertical standards mounted on a hand-car, the clutch-bar provided with depending arms or studs on its ends, 40 the raising-bars swiveled at their lower ends in the ends of the clutch-bar and provided with the hooks or cams $h' h'$, and the levers connected to the upper ends of the raising-bars and adapted to engage suitable racks on 45 the standards, in combination with the vertical shaft K, provided at its lower end with a finger, k, to engage the clutch-bar J, and at its upper end with a hand-wheel, k', and having the lateral arms N N, connected at their ends 50 to the ends of similar arms, O O, on the raising-bars by the links P P, all constructed and arranged substantially as specified.

In testimony that I claim the foregoing as my own I have hereto affixed my signature in presence of two witnesses. 55

MARTIN LEE.
